OSCAR A. THELIN, OF HORTEN, NORWAY, ASSIGNOR TO ELECTRIC BOAT COMPANY, A CORPORATION OF NEW JERSEY.

TORPEDO-LAUNCHING APPARATUS.

1,315,535.

Specification of Letters Patent.

Patented Sept. 9, 1919.

Application filed February 8, 1918. Serial No. 215,960.

To all whom it may concern:

Be it known that I, OSCAR A. THELIN, a subject of the King of Norway, residing at Horten, Norway, have invented certain 5 new and useful Improvements in Torpedo-Launching Apparatus; and I do hereby declare the following to be a full, clear, and exact description of the invention, such as will enable others skilled in the art to 10 which it appertains to make and use the same.

This invention relates to improvements in mechanism for firing torpedoes, particularly installations in which compressed air is admitted to the rear portion of a torpedo-tube 15 to expel a torpedo therefrom.

The invention is directed to the provision of a torpedo launching apparatus of an improved construction in which the torpedo 20 expelling devices and the breech and muzzle doors of the torpedo tube are interlocked so that one door can be opened only when the other is locked closed and so that the expelling devices are rendered operative only 25 when the muzzle door is open and the breech door locked closed. The several interlocks are combined in a single compact structure, preferably mounted on a single support carried by the tube adjacent to the breech end 30 thereof, and therefore conveniently located for inspection, replacement and repair. An operating device is provided near the breech end of the tube for opening and closing the muzzle door, and at least one mechanical element of each of the various interlocks is connected to this operating device so as to be 35 actuated thereby.

Other features of the invention together with the advantages inherent therein will be 40 understood by reference to the following description in connection with the accompanying drawings showing the construction which constitutes the preferred embodiment of the invention.

45 In these drawings, Figure 1 is a vertical section taken transversely through a submarine boat and showing in elevation the breech end of an installation including two torpedo tubes; Fig. 2 is a section on the line 2—2 of Fig. 1; Fig. 3 is an enlarged detail view partly in plan and partly in section; Fig. 4 is a section on the line 4—4 of Fig. 3; Fig. 5 is a section on the line 5—5 of Fig. 3; Fig. 6 shows the parts of Fig. 5 when viewed 50 in the direction of the arrow 6 of Fig. 5;

Fig. 7 is a section, on an enlarged scale, taken on the line 7—7 of Fig. 4; Fig. 8 is a section on the line 8—8 of Fig. 7; and Fig. 9 is a top plan view of the muzzle end of a 60 torpedo tube.

Referring to Figs. 1 and 2, the installation shown consists of a pair of torpedo-tubes 9 mounted one above the other at the bow of a submarine boat. The installation includes a tube-selector valve 11 which is 65 an ordinary rotary valve, having a handle 11^b fixed to its valve spindle 11^a actuatable to so set the valve as to place either a pipe 13 or a pipe 13' in communication with a pipe 12. Pipe 13 is selected when it is desired to 70 discharge a torpedo from upper tube 9; and pipe 13' is selected when it is desired to discharge a torpedo from the lower tube. Pipe 13 leads to a pipe 16, and pipe 16 leads to the torpedo expulsion valve 17 of the 75 upper tube 9. Pipe 13' leads to a pipe 16' which leads to the torpedo expulsion valve 17' of the lower tube. Pipe 12 receives compressed air from a pipe 14 leading from a suitable source, when a firing valve 15 is 80 opened by actuating the lever 15^a.

The expulsion valve 17 of the upper tube is connected to a compressed air conduit 18; and the expulsion valve 17' of the lower tube is similarly connected to a compressed 85 air conduit 18'. These valves 17 and 17' are of the usual balanced type. When air is fed from the pipe 16 to the expulsion valve 17, the valve is unbalanced, a piston-rod 17^a (see Fig. 2) is moved to the right and 90 retracts the torpedo stop block (not shown) by means of a link 17^b, and torpedo-expelling air is admitted to the upper tube from the conduit 18 by way of the connection 17^c. A similar action takes place with respect to 95 the lower tube when air is admitted from pipe 13' to pipe 16', the construction of the two tubes and their associated parts being the same except as may be noted herein.

An interlock valve 19 is carried by a 100 bracket 19', mounted on the right-hand side of upper tube 9, the valve being interposed between pipes 13 and 16. The interior construction of this valve is shown in Figs. 7 and 8. The valve comprises a housing 19^a having a sleeve 19^b fixed therein provided with lateral ports 19^c and 19^d. A rotary spindle having a conical main body 19^e and reduced terminal portions 19^{e'} and 19^{e''} 105 works in the sleeve 19^b; the spindle having 110

formed therein a central passage 19^a closed at one end by a screw cap 19^{a'} and communicating with ports 19^e and 19^f. The housing 19^a has an induction port 19^g, into 5 which is threaded pipe 13 (as shown in Fig. 2), and with an eduction port 19^h where the pipe 16 is threaded into the housing as shown in Fig. 3. An end cap 19^e cages an expansile spring 19^h on the portion 19^g of the spindle. When the spindle 19^e is in the position in which it is shown in Fig. 8, communication between the pipes 13 and 16 is shut off, but when the spindle is moved from that closed or inoperative position to the 10 open or operative position, the port 19^e is carried into registry with the ports 19^e and 19^{e''} and the port 19^f is carried into registry with the ports 19^f and 19^{f''}, thereby connecting pipe 16 to pipe 13. The reduced 15 terminal portion 19^e of the spindle 19^e has a disk 20 (Figs. 4 and 5) fixed thereon provided with arms 20^a and 20^b. The arm 20^b is connected to one end of a retractile spring 21 which normally holds the disk 20 and 20 the spindle 19^e to which it is connected in the position for maintaining the interlock valve closed. The arm 20^a of the disk 20 is arranged in the path of movement of an arm 23 fixed on a shaft 24 so that when the 25 arm is moved from the position in which it is shown in full lines in Fig. 6 to the position indicated by the dot and dash line in that figure, it engages the arm 20^a of the disk 20 and moves that arm and the spindle 19^e to which it is affixed, to the position for 30 opening the interlock valve 19. The shaft 24 is rotated to move the arm 23 over this range when the main shaft 27 of the torpedo launching apparatus is turned to open 35 the muzzle door of the tube by means of a worm 26 on the shaft 27 meshing with a worm wheel 25 on the shaft 24.

The muzzle door is shown at 28 in Fig. 9. The outer end of shaft 27 is threaded 40 and enters a threaded bore in an axially movable cylindrical member 29 located in a cylindrical opening in a bulkhead which supports the muzzle end of the torpedo tubes. The member 29 is connected by a 45 link 30 to one end of a bell-crank lever 31 fulcrumed at 32 and having its opposite end pivotally connected to a lug 28' cast upon the muzzle door 28. When the operating shaft 27 is rotated, the cylinder 29 is moved 50 in the direction of its axis and thus operates through the link 30 and bell-crank lever 31 to swing the muzzle door 28 from the closed position in which it is shown in Fig. 9 to an open position out of the line of fire of 55 the torpedo tube or vice versa.

The breech door 34 of each tube is of the well known hinged type having its periphery threaded to coact with threads on the interior of a breech ring 35, the exterior of 60 which is provided with a plurality of lock-

ing lugs or segments 35^a (Figs. 3 and 4). When the breech door 34 with its ring 35 is swung to the closed position, the lugs 35^a pass through spaces between corresponding lugs on the tube 9 and the ring 35 is then 70 rotated a small amount to carry its lugs 35^a behind the corresponding lugs 9^a on the tube.

The operating mechanism for opening the muzzle door cannot be operated when the breech door is opened. For this purpose a 75 ratchet wheel 36 is keyed on the operating shaft 27 and coacting with this ratchet is a lever 37 pivotally mounted on the bracket 19' with one of its arms 37^a extending through a slot 19^m in the bracket 19' and a 80 slot 9^m in the breech end of the tube 9. The end of this arm 37^a of the lever projects into the path of movement of one of the lugs 35^a of the breech ring 35. The lever 37 has two other arms 37^b and 37^c, the latter of which 85 has a claw 37^c adapted to coact with the teeth of the ratchet 36 on operating shaft 27. The arm 37^b has one end of a spring 38 attached thereto and the opposite end of the spring is connected to a stud 38' on the 90 tube 9. Fig. 4 shows the breech door in the closed position with its lugs 35^a behind the lugs 9^a of the tube. In locking the door in this position, the ring 35 was moved in the direction of the arrow designated C on Fig. 95 4, and as the ring was moved in this direction the lug 35^a engaged the end of arm 37^a of lever 37 and locked that lever against the tension of the spring 38. This movement of lever 37 effected by the lug 35^a carried the 100 lever 37 from the position indicated by the dotted lines in Fig. 4 to the position in which the lever 37 is shown in full lines. In the dotted line position, the claw 37^c of the lever 37 engages the teeth of the ratchet 105 36 on operating shaft 27 so as to preclude rotational movement of the shaft 27 required for opening the muzzle door. The movement of the lever 37 to the full line position shown in Fig. 4 incident to locking 110 the breech door of the tube, carried the claw 37^c away from the ratchet 36, thereby leaving the shaft 27 free to be rotated to open the muzzle door. These parts, therefore, 115 constitute an interlock which prevents opening of the muzzle door except when the breech door is closed and locked in the closed position by the coacting lugs 35^a and 9^a.

Means are also provided for preventing 120 opening of the breech door except when the muzzle door is closed. For this purpose a lever 40 is pivotally mounted upon the under side of the bracket 19' at 40' and one arm of this lever is pivotally connected to a locking bolt 41. The bolt 41 is adapted to be moved 125 back and forth in the direction of its length in an opening 41^a provided for its reception in the breech end of the tube 9, as shown in Figs. 3 and 6, and the movement of this bolt carries its end into and out of the path of 130

movement of one of the locking lugs 35^a of the breech ring 35. The position of the end of bolt 41 with respect to the locking lug 35^a with which it coacts is shown in Fig. 4. 5 When the bolt has been moved to its operative position, as shown in Fig. 4, rotation of the breech ring to permit opening the breech door is precluded. On the other hand, when the bolt 41 is retracted to the position in 10 which it is shown in Fig. 3, the breech ring 35 may be rotated and the breech door opened. The lever 40 is provided with an arm 40^a which is adapted to be engaged by the end of the arm 23 on the shaft 24 to turn 15 the lever 40 on its pivot against the tension of the spring 21 heretofore referred to as connected to one of the arms of the disk 20 for operating the interlock valve. The opposite end of this spring 21 is connected to 20 the end of a third arm on the lever 40.

Referring to Figs. 1 and 2, the upper end of the vertical shaft 24 extends into a fixed signal-box 42 provided with a suitable transparent window or opening 42^a. A signal drum 43 is carried by the portion of the shaft 24 which extends into the signal-box. With the parts arranged as shown in the drawings, that is, with the muzzle door closed, the drum 43 displays through the 30 opening 42^a the word "Closed." The drum may also carry the word "Open" or an equivalent indication, so positioned on the drum that when the horizontal shaft 27 is rotated sufficiently to open the muzzle door, 35 the word "Open" will be displayed through the opening 42^a.

The operation of the apparatus will now be described. Normally the muzzle door of the tube is closed. The breech door may 40 then be opened, as the bolt 41 for locking the breech door is held in its retracted position against the tension of spring 21 by the arm 23 engaging the end 40^a of lever 40. A torpedo having been placed in the tube, the 45 breech door 34 is closed and the breech ring 35 is rotated a distance sufficient to carry the lugs 35^a behind the lugs 9^a on the breech of the tube. While the breech is open, it is impossible to open the muzzle door, as rotation 50 of the horizontal operating shaft 27 is prevented by the engagement of the claw 37^c of lever 37 with the ratchet 36. However, as soon as the breech door is closed and its ring rotated to carry the lugs 35^a behind the 55 lugs 9^a on the tube, the claw 37^c is carried away from the ratchet 36 on shaft 27 against the influence of spring 38 as shown in Fig. 4 to permit of opening the muzzle door.

With the breech door closed and the claw 60 37^c freed from the ratchet 36, the gunner may now turn the handle 33 and rotate the shaft 27 to open the muzzle door 28. The shaft 24 is turned with the shaft 27 through the worm gearing connecting them and the 65 first part of the rotational movement carries

the arm 23 in an anti-clockwise direction, as seen in Fig. 6, away from the arm 40^a of lever 40, permitting the spring 21 to move the bolt 41 into position to lock the breech door closed. As the shaft 27 is rotated further, the muzzle door opens more and more and when it is fully opened, the drum 43 on the upper end of the shaft 24 no longer shows the "closed" signal at the signal box 42. Just before the muzzle door is fully 70 opened, the arm 23 on the shaft 24 assumes the broken-line position of Fig. 6, the tip of the arm 23 engages the arm 20^a on the spindle of the interlock valve 19 and the interlock valve is opened. Thus, when the muzzle door is fully opened, the breech door is closed and locked closed, the signal-box 43 displays the word "Open," and the interlock valve is held in the open position.

The gunner may have previously set the 85 tube-selector valve 11 of Fig. 1 to place the pipes 12 and 13 in communication, or he may now so adjust the tube-selector valve. In either case, subsequent opening of the firing valve 15 will discharge the torpedo by 90 admitting compressed air through pipe 12, tube-selector valve 11, pipe 13, interlock valve 19 and pipe 16 to actuate valve 17 and thereby admit torpedo-expelling air from conduit 18 through connection 17^c to the 95 tube 9.

After a torpedo has been launched, the gunner turns handle 33 and shaft 27 so as to close the muzzle door. Until this is done, it is impossible to open the breech door, 100 since the latter is locked by the bolt 41. On turning the shaft 27 to close the muzzle door, the arm 23 moves in a clockwise direction as shown in Fig. 6, and first draws away from the arm 20^a and so permits the interlock 105 valve 19 to be closed by spring 21 and thereafter the arm 23 engages the arm 40^a of lever 40 and retracts the locking bolt 41 of the breech door to unlock the breech ring 35. At the conclusion of the operation of 110 closing the muzzle door, the drum 43 will again display the "closed" signal. When the muzzle door has been closed and the bolt 41 retracted, the breech ring 35 may be turned in the direction of the arrow O 115 of Fig. 4 to permit opening the breech door. When this is done, the spring 38 forces the claw 37^c of the lever 37 into engagement with the ratchet 36 on shaft 27, thereby locking the muzzle door closed.

It will thus be seen that there is provided a safety operating mechanism for a torpedo-tube characterized by the provision of means for preventing either the breech door or the muzzle door of the tube being opened except when the other is closed, means for preventing an effective actuation of the firing-valve except when the muzzle door is open and the breech door is locked closed, and means for indicating whether the muzzle 130

4

door is closed or open. By this construction, opening of the muzzle door necessitates several rotations of shaft 27, and consequently long before the muzzle door is opened 5 sufficiently to admit any considerable amount of sea water to the interior of the tube by way of the muzzle, the bolt 41 will have been actuated to lock the breech door closed. The various interlocks, mechanical and pneumatic, are parts of a compact organization, located adjacent the breech end of the tube and therefore conveniently accessible for inspection, replacement and repair.

I claim:

- 15 1. A torpedo launching apparatus comprising the combination of a tube, a breech door, a muzzle door, a shaft rotatable to open and close the muzzle door, a single support mounted adjacent to the breech end 20 of the tube and having a bearing for said shaft therein, a ratchet wheel on the shaft, a lever pivoted on said support in position to engage said ratchet and to be actuated by the breech door, a second lever pivoted on 25 said support, a lock for the breech door actuated by the second lever, and means actuated by rotation of the shaft for operating the second lever; substantially as described.
- 30 2. A torpedo launching apparatus comprising the combination of a tube, a breech door, a muzzle door, a shaft rotatable to open and close the muzzle door, a single support mounted adjacent to the breech end 35 of the tube and having a bearing for said shaft therein, a ratchet wheel on the shaft, a lever pivoted on said support in position to engage said ratchet and to be actuated by the breech door, a second lever pivoted 40 on said support, a lock for the breech door actuated by the second lever, a valve mounted on said support and controlling the admission of air to the tube, and means actuated by the rotation of the shaft for operating 45 said second lever; substantially as described.
- 50 3. A torpedo launching apparatus comprising the combination of a tube, a breech door, a muzzle door, a shaft rotatable to open and close the muzzle door, a bracket secured to the tube near the breech end there- 55 of and having a bearing formed therein for said shaft, a ratchet wheel on the shaft, a lever pivotally mounted on the bracket and adapted to be operated by the breech door to cause it to engage said ratchet, a second lever pivoted on the bracket, a lock for the breech door actuated by the second lever, and means actuated by rotation of the shaft for operating 60 the second lever; substantially as described.
- 65 4. A torpedo launching apparatus comprising the combination of a tube, a breech door, a muzzle door, a shaft rotatable to open and close the muzzle door, a bracket secured to the tube near the breech end

thereof and having a bearing formed therein for said shaft, a ratchet wheel on the shaft, a lever pivotally mounted on the bracket and adapted to be operated by the breech door to cause it to engage said ratchet, a second 70 lever pivoted on the bracket, a lock for the breech door actuated by the second lever, a valve mounted on the bracket and controlling the admission of air to the tube to expel a torpedo therefrom, and means actuated by the rotation of the shaft for operating said second lever; substantially as described.

5. A torpedo launching apparatus comprising the combination of a tube, a muzzle 80 door, a breech door, means for opening and closing the muzzle door including a rotary member carrying a worm, a worm gear meshing with the worm, an arm mounted for movement with the worm gear, and a spring- 85 actuated locking device for the breech door moved by said arm, the locking device being movable to operative and inoperative positions when the muzzle door is opened and closed; substantially as described.

90 6. A torpedo launching apparatus comprising the combination of a tube, a breech door, a muzzle door, a lever, a locking bolt for the breech door connected to the lever, a spring associated with the lever for mov- 95 ing the bolt to its operative position, a shaft which is rotatable for opening and closing the muzzle door, and an arm rotatable as said shaft is rotated and adapted to engage the lever to hold the bolt inoperative when the muzzle door is closed, and to disengage the lever when the muzzle door is opened; substantially as described.

100 7. A torpedo launching apparatus comprising the combination of a tube, torpedo 105 launching means including an air line having a normally closed valve interposed therein, a muzzle door, means for opening and closing the muzzle door including a rotatable shaft, a worm carried by the shaft, 110 a gear meshing with the worm, and a member movable with said gear for opening the valve when the shaft has been rotated to open the muzzle door; substantially as described.

115 8. A torpedo launching apparatus comprising the combination of a tube, a muzzle door, means for opening and closing the muzzle door including a rotatable shaft, a worm fixed on the shaft adjacent the breech 120 of the tube, a second shaft, a signaling device on the second shaft, a worm gear fixed on the second shaft and meshing with said worm, an arm mounted to move with the worm gear, and torpedo launching means 125 including an air line having a spring-closed interlock valve interposed therein, the stem of which is engaged by said arm to open the valve when said shaft is rotated to open the muzzle door; substantially as described. 130

9. A torpedo launching apparatus comprising the combination of a tube, a breech door, a muzzle door, a shaft extending lengthwise of the tube, rotatable for opening and closing the muzzle door, a spring actuated locking device for the breech door, a spring-actuated valve controlling the supply of compressed air to the tube to expel a torpedo therefrom, a second shaft geared 10 to said shaft, and an arm carried by the second shaft, which, when the second shaft is turned in one direction is adapted to actuate said lock and when the second shaft is turned in the other direction is adapted to 15 actuate said valve; substantially as described.
10. A torpedo launching apparatus comprising the combination of a tube, a breech door, a muzzle door, a shaft extending 20 lengthwise of the tube and rotatable to open and close the muzzle door, a vertical shaft geared to said shaft by worm gearing, a signaling device on the vertical shaft, a spring-actuated lock for the breech door, a 25 spring-actuated valve for controlling the
- supply of compressed air to the tube to expel a torpedo therefrom, and an arm on the vertical shaft engaging said lock when it is moved in one direction and said valve when it is moved in the other direction; substantially as described. 30
11. A torpedo launching apparatus comprising the combination of a tube, a breech door, a muzzle door, a shaft extending lengthwise of the tube, rotatable to close 35 and open the muzzle door, a ratchet on said shaft, a spring-actuated lever operated by the breech door and coacting with said ratchet to prevent rotation of said shaft, a spring-actuated lock for the breech door, a 40 spring-actuated valve controlling the supply of air to the tube to expel a torpedo therefrom, a second shaft connected to said shaft by worm gearing, and an arm on the second shaft movable in one direction to operate 45 said lock and in the other direction to operate said valve; substantially as described.

In testimony whereof I affix my signature.

OSCAR A. THELIN.
